(57) CLAIM

The ornamental design for a ceramic tile, as shown and described.

DESCRIPTION

FIG. 1 is a front-side perspective view of a first embodiment of a ceramic tile, showing my new design;

FIG. 2 is a front view thereof;

FIG. 3 is a back view thereof;

FIG. 4 is a top edge view thereof, the bottom edge view, left side edge view and right side edge view thereof being identical thereto;

FIG. 5 is a front-side perspective view of a second embodiment of a ceramic tile according to the invention;

FIG. 6 is a front view thereof;

FIG. 7 is a back view thereof;

FIG. 8 is a top edge view thereof, the bottom edge view thereof being identical thereto; and,

FIG. 9 is a right side edge view thereof, the left side edge view thereof being identical thereto.
